UNITED STATES PATENT OFFICE.

ROY M. WITT, OF TAMPA, FLORIDA.

TUBE.

Application filed June 18, 1926. Serial No. 116,968.

This invention relates to improvements in tubes for holding paste and the like, the general object of the invention being to provide means for opening and closing the mouth of the tube by a valve-like member so as to eliminate the use of a cap or the like.

Another object of the invention is to provide a handle for the valve-like member which is movable in a small arc of a circle so that the tube can be easily opened and closed by a slight movement of the handle.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a sectional view through a tube, showing the invention in use.

Figure 2 is a similar view, but showing the valve in open position.

Figure 3 is an elevation of the improved tube.

Figure 4 is a section taken at right angles to Figure 1.

Figure 5 is a top plan view.

Figures 6 and 7 are views of the valve member.

In these views, 1 indicates the tube which is formed with a head 2 having the discharge passage 3 passing therethrough. As shown, this passage is made in the form of an elongated slot. A transverse cylindrical bore 4 is formed in the head and intersects the passage and a cylindrical shaped valve or body 5 is rotatably mounted in the bore. This body or valve is formed with a diametrical slot 6 which, when the valve is turned to a certain position, will register with the passage and thus permit some of the contents of the tube to pass therefrom when the tube is squeezed. In another position of the valve or body, the slot will extend at right angles to the passage and thus the passage will be closed by the solid portion of the valve or body. A slot 7 is also formed in the valve or body and extends from one wall of the slot 6 through a side of the body and this slot 7 is so arranged

that when the body is in a position with the slot 6 extending crosswise of the passage, the slot 7 will register with the upper part of the passage 3 and thus be in communication with the interior of the tube, as shown in Figures 1 and 4. This will prevent the material in the passage 6 from becoming hard or dry as it will be kept moist by being in communication with the material within the tube.

A yoke-shaped handle 8 has its ends connected with the ends of the valve and the central part of its bight is provided with a loop 9 which forms a finger engaging part 70 so that the handle can be moved from one position to another to open or close the valve. Shoulders 10 and 10' are formed on the head and act as stops for the handle.

From the foregoing, it will be seen that with the parts in a position as shown in Figure 1, the passage 3 will be closed, though the slot 6 will be in communication with the interior of the tube so that the material in said slot will be prevented from becoming hard and dry. By pressing the handle over against the shoulder 10', as shown in Figure 2, the slot 6 will register with the passage 3 so that material can pass through the head.

Thus I have produced a simple and effective closure for a tube. The closure can be easily moved to open or closed position by simply pushing the handle from one position to the other.

This device will eliminate the use of a cap which is often lost and which takes time to screw on and unscrew from the tube.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A tube for paste and the like comprising a head having a discharge passage therein and a bore intersecting the passage, a rotary valve in the bore and having a slot therein for registering with the passage when the valve is moved to a certain position, a yoke shaped handle connected with the ends of the valve for moving the same, said valve having a slot leading from the first slot through one side of the valve for

placing said first slot in communication with the interior of the tube when the valve is in closed position and the head having shoulders thereon for limiting the movement 5 of the handle.

2. A tube for paste and the like comprising a head having a discharge passage therein and a bore intersecting the passage, a rotary valve in the bore and having a slot 10 therein for registering with the passage when the valve is moved to a certain position, a handle connected with the valve for

moving the same, said valve having a slot leading from the first slot through one side of the valve for placing said first slot in 15 communication with the interior of the tube when the valve is in closed position and the head having shoulders thereon for limiting the movement of the handle, one shoulder acting to stop the parts with the 20 slot in the side of the valve in communication with the tube.

In testimony whereof I affix my signature.
ROY M. WITT.
